UNITED STATES PATENT OFFICE.

WILLIAM H. PEEPS, OF CINCINNATI, OHIO, ASSIGNOR TO THE BRUNSWICK-BALKE-COLLENDER COMPANY, OF SAME PLACE.

DESIGN FOR A BACK BAR.

SPECIFICATION forming part of Design No. 23,028, dated January 30, 1894.

Application filed October 30, 1893. Serial No. 489,566. Term of patent 14 years.

To all whom it may concern:

Be it known that I, WILLIAM H. PEEPS, a citizen of the United States, residing at Cincinnati, in the county of Hamilton and State 5 of Ohio, have invented and produced a new and original Design for a Back Bar or Counter, of which the following is a specification, reference being had to the accompanying drawings, forming a part thereof.

10 In my new design, the end portion of the shelf of the back-bar is cut out on a quarter circle, to permit the presence of a column, circular in cross-section, which extends below the level thereof, and the said column has its 15 base located on the floor, on which the bar rests. The presence of this column, partially in the niche in the end of the back-bar, forms the characteristic feature of my invention.

10 In the accompanying drawings which form 20 part of this specification, Figure 1 is a view in perspective of a bar out-fit comprising my new design. Fig. 2 is a partial horizontal section at the line x, x , of Fig. 1.

25 In the drawings B is the usual front, or main, bar, in rear of which is the back-bar that comprises a shelf-like portion, or counter, C, and a mirror-frame D, about equal in length, and each of about the same length as the front bar B; the said back-bar being 30 mounted with an entablature E.

At each end of the back-bar is a round column G (having a capital h , and base i) the pedestal J of which rests upon the floor on

which rest the bases of the main and back-bars; and, for the accommodation of this column G, or to permit it to extend from the entablature E clear down past the shelf-like part C, of the back-bar, the end portion of said shelf is cut away, or hollowed out, by a quarter circle cut-out, as seen at m . (See 35 40 particularly Fig. 2.)

It will be observed that a novel and unique appearance results, especially when the bar fixture is viewed from a point from which its end-portion is clearly seen, from the presence 45 of the long column G having its base and the lower portion of its round body located within the curved niche, or cut-out m , of the back-bar shelf, as shown and described; and this novel appearance lends to my design its characteristic 50 feature.

Having now so fully shown and described my new design that those skilled in the art can readily manufacture back bars in accordance with my invention, what I claim is— 55

The herein shown new design for back-bars; the essential, or characteristic, features of which are the long round-body column G, and the curved, niched, back-bar end m ; all as hereinbefore described.

In witness whereof I have hereunto set my hand this 23d day of October, 1893.

WILLIAM H. PEEPS.

In presence of—

JULIUS BALKE,
C. D. TALBOTT.
